TILTING PLATFORM TRAILER

Jack E. Moll, New Berlin, Wis., assignor to Miller Tilt-
Top Trailer, Inc., Milwaukee, Wis., a corporation of Wisconsin

Filed July 19, 1965, Ser. No. 86,206

Term of patent 14 years

(Cl. D14—3)

FIG. 1 is a view of the tilting platform trailer from the top.

FIG. 2 is a view of the tilting platform trailer from the top with the tilt section raised.

The dominant features reside in the solid line portions.

I claim:

The ornamental design for a tilting platform trailer, substantially as shown and described.
